VARIABLE RATIO TRANSFORMER

Marion L. Roberts, Portland, Oreg., assignor to Osborne Electronic Corporation, Portland, Oreg., a corporation of Oregon

Filed Jan. 30, 1961, Ser. No. 85,744

8 Claims. (Cl. 323—45)

This invention relates to electrical transformers in general, and to variable ratio transformers in particular in which the output voltage is at least in part obtained from secondary windings and in which the input to output voltage ratio can be adjusted to any of a large number of values in order to provide a selected ratio whose value will be precisely known. These precision transformers are useful in performing many types of electrical test measurements and the like.

It is well known to provide transformers of the general type above referred to in which the ratio of input voltage to output voltage can be selected from a number of different values. When these types of transformers are used for very precise measuring or controlling functions under no load conditions, their transformation ratios must be known with an accuracy that is much greater than that of the ordinary transformer. While the precision ratio transformers of the prior art have been carefully constructed so that their primary windings and secondary windings are evenly distributed and have the exact number of turns required for a turns ratio which should result in the desired transformation ratio of input voltage to output voltage, this has not been the case because the resultant output voltage is not in phase with the applied input voltage and is not equal in magnitude to the applied voltage multiplied by the turns ratio of the transformer. The major cause of this inaccuracy is due to the fact that even under no load condition the exciting current flowing in primary windings causes an internal voltage drop due to the winding resistance and leakage reactance of the primary windings. The result is that the voltage appearing across the secondary windings consists merely of the voltage induced therein due to the mutual flux in the magnetic core of the transformer so that it is less than the applied primary voltage multiplied by the turns ratio and is also somewhat out of phase with the applied primary voltage. This presents a problem when it is desired to employ the secondary voltage, in whole or in part, to provide a plurality of output voltages which are accurately related to the applied primary voltage as fractions or multiples thereof.

In order to overcome this problem, the present invention makes use of a compensation impedance connected in series with the primary windings of the precision ratio transformer to add a compensating voltage, developed across this compensation impedance by primary current flowing therethrough, to the voltage induced in the secondary windings so that the output voltage of the transformer is more nearly in phase with its input voltage and the output voltage is more closely equal to the input voltage multiplied by the turns ratio of the transformer.

In one form, this compensation impedance is divided into a plurality of impedance steps corresponding in number to a plurality of voltage steps in the secondary windings of a transformer forming part of a precision ratio transformer apparatus. Selected portions of this compensation impedance can be connected in series with selected portions of the secondary windings of the transformer so that a compensation voltage in phase with the voltage drop due to the impedance of the primary windings is added to the induced voltage in such portions of the secondary windings. For example, the impedance steps of the compensation impedance can be selectively connected in series with the voltage steps of the second-

2

ary windings by means of a switch ganged with the voltage selection switch for the secondary windings. This enables the proper amount of compensating voltage having a correct phase angle to be added to each step of the induced secondary voltage. The vector sum of such voltage is an output voltage which is more nearly in phase with the applied input voltage of the transformer and more nearly equal to the applied voltage multiplied by the turns ratio.

10 In another form, a compensation impedance is connected in series with the primary windings of a transformer forming a part of the variable ratio transformer apparatus and the compensating voltage developed across such compensation impedance is added to the voltage developed in the secondary windings of such transformer by means of another transformer having a proper turns ratio and having its primary windings connected across the compensation impedance and secondary windings connected in series with the secondary windings of the transformer to which the compensation is being applied.

20 Therefore, one object of the present invention is to provide a compensation circuit which provides compensation to the secondary windings for the impedance voltage drop in the primary windings of a precision transformer.

25 Another object of the invention is to provide a variable ratio transformer having a compensation impedance to correct the improper voltage transformation, in the form of inaccurate magnitude ratios and phase shift of output voltage to input voltage, in the transformer due to the internal voltage drop in the primary windings thereof.

30 A further object of this invention is to provide a precision transformer of the variable ratio type having a compensation impedance to correct for the voltage drop in the primary windings of the transformer when such transformer is under a no load condition.

35 Still another object of the present invention is to provide a test circuit for measuring the characteristics of transformers, or other electrical devices, by variable ratio transformers having compensation circuits to correct for the voltage drop in the primary windings thereof so that they may be used as accurately calibrated standards in such test circuit.

40 Other objects and advantages of the present invention will be apparent when referring to the following detailed description of preferred embodiments of the invention, given by way of example and described in connection with the attached drawings, of which:

45 FIG. 1 is a schematic diagram of the electrical circuit 50 of a variable ratio transformer in accordance with the present invention;

55 FIG. 2 is a vector diagram illustrating the relative magnitudes and phase relationships of various voltages and currents and the mutual flux related to the primary windings of the variable ratio transformer of FIG. 1;

60 FIG. 3 is a vector diagram of part of the output voltage from one portion of the variable ratio transformer in FIG. 1; and

65 FIG. 4 is the schematic diagram of a test circuit in accordance with the present invention using the variable ratio transformer of FIG. 1.

70 The schematic diagram illustrated in FIG. 1 shows the electrical circuit used in the variable ratio transformer apparatus of the present invention and the voltage compensation circuit used therein. This apparatus includes five separate transformers, T_1 , T_2 , T_3 , T_4 and T_5 , each having a separate core of ferromagnetic material. Such transformers are arranged so that their output windings may be connected in series so the voltage developed across each of these windings can be added thereby. This arrangement gives a final output voltage which is the sum of the series added voltages. Step down trans-

former T_1 has primary windings A_1 which are connected across a source of A.C. voltage, shown as an A.C. line including conductors indicated by terms "HIGH" and "LOW." Primary windings A_1 of transformer T_1 are shown as being divided into ten equal voltage steps which can be selectively connected by switch S_1 in series between the line conductor marked "LOW" and the lower end of secondary windings B_1 positioned on a common magnetic core with primary windings A_1 . It should be noted here that while each of the windings on step down transformers T_1 , T_2 and T_3 have been shown to be divided into ten equal steps each, that it is possible to divide these windings into any number of equal or unequal voltage steps. It should be understood that the only reason for using a decade arrangement of ten equal steps is to enable the utilization of the decimal system in computing the voltage transformation ratio. Secondary windings B_1 of step down transformer T_1 also have a decade arrangement so that they are divided into ten equal voltage steps which are in turn selectively connectable by switch S_2 in series between the switch S_1 and lower end of secondary windings C_1 . Secondary windings C_1 are similarly divided into a decade arrangement of ten equal steps which are selectively connectable by switch S_3 in series between the switch S_2 and the lower end of primary windings A_2 of transformer T_2 .

Primary windings A_2 of step down transformer T_2 are connected across secondary windings D_1 of transformer T_1 so that the voltage across secondary windings D_1 is used as the input voltage of transformer T_2 . Primary windings A_2 and secondary windings B_2 , C_2 and D_2 along with their associated switches, S_4 , S_5 and S_6 can be identical to the similar parts of transformer T_1 . Any number of step down transformers similar to T_2 may be connected in series therewith in order to obtain the degree of precision desired. The final step down transformer T_3 is connected with its primary winding A_3 across secondary windings D_2 of transformer T_2 so that the voltage across secondary windings D_2 serves as the input voltage of transformer T_3 . Primary windings A_3 also have a decade arrangement whose equal voltage steps are connectable by switch S_7 in series between switch S_6 and the lower end of secondary windings B_3 on transformer T_3 . Secondary windings B_3 are likewise provided with a decade arrangement of equal voltage steps connectable by means of switch S_8 in series between the switch S_7 and the lower end of secondary windings B_5 of transformer T_5 . It will be apparent that the transformers T_4 and T_5 will be by-passed if the switch S_9 is in its lowermost position 1X.

In this arrangement each step of primary windings A_1 has one-tenth of the input voltage V_1 across its terminals while each step of secondary windings B_1 has induced therein somewhat less than one-tenth of the voltage across each step of primary windings A_1 , or somewhat less than one-hundredth of the input voltage V_1 , since there is a ten-to-one turns ratio between windings A_1 and B_1 . Secondary windings C_1 have one-tenth of the voltage developed across each step of secondary B_1 induced in each of its individual steps, or somewhat less than one-thousandth of the input voltage V_1 , since there is a similar ten-to-one turns ratio between windings B_1 and C_1 . The voltage developed across secondary windings D_1 is equal to the voltage induced in one step of secondary windings C_1 due to a ten-to-one turns ratio between windings C_1 and D_1 . Each step of primary windings A_2 has induced therein one-tenth of the voltage across secondary windings D_1 or approximately one ten-thousandth of input voltage V_1 of step down transformer T_2 . In a similar manner secondary windings B_2 have induced in each step thereof a voltage of approximately $10^{-5} V_1$, secondary windings C_2 have induced in each of its steps approximately $10^{-6} V_1$, each step of primary windings A_3 has about $10^{-7} V_1$ induced therein, and finally, secondary windings B_3 have induced

in each of its steps about $10^{-8} V_1$. This is continued until the desired degree of precision is obtained in the final output voltage measured between switch S_8 on transformer B_3 and the "LOW" side of the line. The positions of the various switches associated with transformers T_1 , T_2 and T_3 in FIG. 1 result in an output voltage of approximately 0.36453564 times the input voltage V_1 , between switch S_8 and the "LOW" side of the line.

As shown in FIG. 2 the A.C. input voltage V_1 applied to the primary windings A_1 of transformer T_1 causes an A.C. current I_1 to flow in the primary windings which lags applied voltage V_1 by phase angle θ . Under no load conditions the primary winding current I_1 equals the exciting current for the magnetic core of the transformer. This exciting current I_1 may be resolved into two components, a magnetizing current I_m and a core loss current I_L in quadrature therewith. Magnetizing current I_m produces a mutual flux ϕ which links with the primary windings A_1 and secondary windings B_1 of the transformer. This mutual flux ϕ induces a voltage E_1 in primary winding A_1 which lags the mutual flux by 90 degrees. The core loss current I_L supplies the energy for the hysteresis and eddy-current losses in the magnetic core of the transformer T_1 . When exciting current I_1 flows through primary A_1 , the winding resistance of this primary causes a voltage drop $I_1 R_1$ which is in phase with the exciting current I_1 . Since the leakage flux and its associated leakage reactance can be neglected in a well-designed toroidal transformer, the applied voltage V_1 can be considered to be the vector sum of the induced voltage E_1 and the winding resistance voltage drop $I_1 R_1$.

The voltage developed across the secondary windings B_1 when no load is applied to such secondary windings consists only of the voltage E_2 which is induced in secondary windings B_1 by mutual flux ϕ as shown in FIG. 3. This induced voltage E_2 is in phase with the induced voltage E_1 of primary windings A_1 since primary windings A_1 and secondary windings B_1 are on the same magnetic core and are linked by the same mutual flux. Since no current flows in the secondary windings B_1 due to its no load condition, no voltage drop due to the internal resistance or leakage reactance of the windings B_1 is produced. Therefore, the voltage developed across secondary windings B_1 is merely the induced voltage E_2 which is out of phase with the voltage V_1 applied to primary windings A_1 by the phase angle α and is not equal to such voltage multiplied by the turns ratio of windings A_1 and B_1 , the magnitudes of such phase angle α and the voltage $I_1 R_1$ being exaggerated in FIG. 2. That is to say, increments of the induced secondary voltage E_2 do not provide output voltage steps which are in phase with or which have a magnitude equal to the applied voltage V_1 multiplied by the turns ratio so that an inaccuracy occurs.

In order to compensate for the inaccuracy discussed above selected portions of a compensation impedance, which may be suitable tapped resistor R_c , are connectable in series with primary A_1 by means of a switch S_c ganged with the switch S_2 for secondary windings B_1 . Compensation resistor R_c is divided into a plurality of resistance steps corresponding in number to the voltage steps of secondaries B_1 . As a result the combined output voltage of each selected step of secondary windings B_1 and the corresponding step of compensating resistor R_c consists of a fraction E_2' of the induced voltage E_2 of secondary windings B_1 and a voltage $I_1 R_c'$ which very closely approaches the fraction of $I_1 R_c$ required to produce a resulting output voltage step in phase with the input voltage V_1 and of the desired magnitude. Since the value of each resistance step of compensating resistor R_c is selected so that it is proportional by the turns ratio to the winding resistance of each voltage step in primary A_1 , primary current I_1 flowing through this compensation resistance produces a voltage drop in phase with and proportional to the resistance voltage drop in the windings

of primary A_1 . When the total compensating resistance voltage $I_1 R_c$ is added to the total induced voltage E_2 of the secondary winding B_1 , the resultant voltage V_2 is obtained as shown in FIG. 3 which is in phase with the primary voltage V_1 applied to the primary A_1 and more nearly equal to the applied voltage multiplied by the turns ratio. The same relation holds for each step of the windings B_1 and compensating resistance R_c as indicated by the voltages E_2' and $I_1 R_c'$ of FIG. 3. It should be noted that the resistance of compensation resistor R_c is small compared to the impedance of primary A_1 so that its effect upon the magnitude and phase angle of applied voltage V_1 can be neglected.

Since step down transformers T_1 , T_2 and T_3 are connected with their output windings in series, the voltages developed across each of their windings are added. It is apparent that voltage compensation similar to that discussed above could be applied to each of the remaining windings of these transformers to obtain an even more accurate transformation. This is not done in practice because the voltages developed across the remaining windings are very small with respect to the voltage developed across primary A_1 so that such compensation is, in general, not necessary.

It is often desirable, however, to add a step up transformer T_4 to the variable ratio transformer apparatus in order to add a multiple of the line voltage to the output voltage of the transformer apparatus. When this is done a compensating impedance in the form of a resistor R_5 is connected in series with the primary windings A_4 of the step up transformer T_4 , since the secondary windings B_4 and C_4 are operated under no load condition and the voltages induced therein are less than the applied voltage times the turns ratio because of the resistance voltage drop in primary windings A_4 . Unlike compensating resistor R_c , the compensating resistor R_5 is not divided into a plurality of resistance steps, but the voltage drop across this compensating resistance is stepped up and added to the voltage induced in secondary windings B_4 and C_4 by means of a compensating transformer T_5 . A step up compensating transformer is required since it is necessary to add a voltage to the output voltage of each of the secondary windings B_4 and C_4 which is equal to the IR drop in primary windings A_4 and compensating resistor R_5 . This transformer T_5 has its primary windings A_5 connected across the compensating resistor R_5 and has its secondary windings B_5 and C_5 connected in series with secondary windings C_4 and B_4 respectively of step up transformer T_4 .

When switch S_9 has its movable contact in the lower position IX in FIG. 1 transformers T_4 and T_5 are bypassed and no multiple of the line voltage is added to the output of the variable ratio transformer apparatus. Also the switch S_{10} is ganged with the switch S_9 to disconnect transformer T_4 from the line when such switches are in the position IX. However, when switches S_9 and S_{10} are in the position 2X, as shown in FIG. 1, the step up transformer T_4 is connected to the line and its secondary windings C_4 are connected in series with the secondary windings B_3 through secondary windings B_5 of the transformer T_5 so that a compensated voltage, which is a multiple of the line voltage is added to the output voltage from windings B_3 . If there is a one-to-one turns ratio between primary winding A_4 and each of the secondary windings B_4 and C_4 , this added voltage will be equal to the line voltage. When switches S_9 and S_{10} are in the position 3X, both secondary windings B_4 and C_4 are connected in series with the output from secondary windings B_3 through secondary windings B_5 and C_5 of transformer T_5 resulting in a compensated voltage equal to two times the line voltage being added to the output from secondary windings B_3 . The turns ratio of compensating transformer T_5 between primary windings A_5 and each of the secondary windings B_5 and C_5 is selected so that the compensating voltage developed across compensating

resistor R_5 is properly transformed in order that the magnitude and phase angle of the compensating voltage so transformed corresponds to that of the resistance voltage drop in primary windings A_4 and R_5 .

This variable ratio transformer with its compensation means may be used to test any electrical device in any test circuit where the transformer is used under no load condition. One such test circuit is shown in FIG. 4 by which other transformers may be tested for their accuracy of voltage transformation. The primary windings of the transformer T_T being tested are connected across an A.C. voltage source E . A variable ratio percentage transformer T_p is connected with its primary windings in parallel with the primary windings of test transformer T_T . The compensated variable ratio transformer T_s of FIG. 1, shown as an auto transformer in FIG. 4 for simplicity, is used as a comparison standard by having one end of its windings connected directly to the low side "LO" of the line, and a selected tap of the primary windings connected in series with the secondary windings of the percentage transformer T_p through switch S_p to the high side "HI" of the line. The secondary windings of test transformer T_T have one end connected directly to the low side of the line, and the other end by switch S_s to a selected voltage output tap on the windings of the standard transformer T_s through an electrical meter M . The secondary windings of the test transformer T_T and the windings of standard transformer T_s are connected to have their voltages oppose or buck each other so that the standard transformer T_s is operated under no load conditions.

When testing for the turns ratio or the accuracy of the voltage transformation ratio of the transformer T_T being tested, the meter M connected in series with the secondary windings of test transformer and the standard transformer is a voltage indicator. The desired voltage transformation ratio may then be set on the compensated variable ratio transformer T_s which is used as a standard because of its precision and accuracy. The contact switch S_p on percentage transformer T_p is then moved until a minimum reading is obtained on the voltage indicator M . Since the secondary windings of percentage transformer T_p are divided into a plurality of percentage steps, the setting of switch S_p on such secondary windings is then read to determine how accurate the transformer under test is compared to the standard transformer T_s . The reading on the percentage transformer T_p given by the setting of switch S_p can be terms of the percentage deviation of the transformer under test T_T from the desired turns ratio set on variable ratio transformer T_s . It is also possible to determine the actual transformation ratio of the test transformer T_T directly from the reading given by switch S_s on standard transformer T_s . In order to obtain this actual ratio directly switch S_p is set at zero on percentage transformer T_p and the switch S_s on standard transformer T_s is moved until a minimum voltage reading appears on voltage indicator M .

It is also possible to accurately determine the phase shift between the input and output voltages of the transformer T_T under test by using the test circuit shown in FIG. 4 when a phase angle meter is substituted for the voltage indicator and connected in the circuit to show the phase angle between the voltage across the test transformer T_T and that across the terminals connected to the meter M in FIG. 4. The output voltage of percentage transformer T_p is set to zero voltage by switch S_p and the standard transformer T_s is adjusted to produce a 90° phase angle reading of the phase meter. This indicates that the voltage across the terminals shown connected to the meter M in FIG. 4 is 90° out of phase with the voltage developed across the output of standard transformer T_s , which voltage is very nearly in phase with the input voltage of transformer T_s with its compensation means. Since at this time the same input voltage is across the primary of both transformers T_T and T_s , the output volt-

age of transformer T_S is very nearly in phase with the input voltage of transformer T_T . Next the switch S_p on percentage transformer T_T is moved from its zero position until the reading of the phase meter is 45° . It can then be shown that the output voltage of transformer T_p divided by the output voltage of transformer T_S is the tangent of the angle of phase difference between the output voltages of transformers T_T and T_S . Since the phase shift of standard transformer T_S is very small or zero with its compensation, this angle is also the phase angle between the input and output voltages of the transformer under test T_T . It should be noted that the frequency of A.C. voltage source E should be near that of the rated frequency of the transformers used in the test circuit of FIG. 4 and that the percentage transformer T_p may have 15 a compensation means similar to that used in standard transformer T_S .

While the present invention has been described above in connection with certain specific embodiments thereof, it should be understood that various modifications as to detail will occur to those skilled in the art and that such modifications which would be obvious to one having ordinary skill are encompassed by the concept of the present invention. Therefore, the scope of the present invention is not limited to the embodiments illustrated, 25 but is defined only in the following claims.

I claim:

1. A precision electrical transformer comprising:
a magnetic core,
primary and secondary windings on said core,
compensation means connected to said secondary winding to produce under no load conditions an output voltage on said secondary winding which is substantially in phase with the input voltage applied to said primary winding and equal to the product of said input voltage multiplied by the turns ratio between said primary and secondary windings,
said compensation means including means to produce a compensating voltage in phase with and equal to the product of the impedance voltage drop in said primary windings multiplied by the turns ratio between said primary and secondary winding and to add said compensating voltage to the voltage induced in said secondary winding under no load conditions. 40
2. A precision electrical transformer comprising:
a magnetic core,
primary and secondary windings on said core,
a compensation impedance connected in series with said primary winding to provide under no load conditions a compensation impedance voltage drop across 50 said compensation impedance in phase with and proportional to the impedance voltage drop in said primary winding due to current flowing in said primary winding, and
means for connecting said compensation impedance 55 to the secondary winding to add to the voltage induced in said secondary winding under no load condition a compensating voltage derived from said compensation impedance voltage drop which is in phase with the impedance voltage drop in said primary 60 winding and equal to the product of said impedance voltage drop in said primary winding multiplied by the turns ratio between said primary and secondary windings.
3. A precision electrical transformer comprising:
a core of magnetic material,
primary windings on said core,
secondary windings on said core divided to provide a plurality of first voltage steps,
a compensation impedance connected in series with 70 said primary windings and divided to provide a plurality of second voltage steps,
a switch to connect a selected number of said first voltage steps in series with the output of said transformer, and

a second switch to connect a corresponding number of said second voltage steps in series with said secondary winding and the output of said transformer so that the effective open circuit output voltage of said secondary windings is equal to the sum of the voltage across said selected steps of said secondary windings and the voltage across said selected steps of said compensation impedance.

4. A precision electrical transformer comprising:
a core of magnetic material,
primary windings on said core,
secondary windings on said core,
compensation resistance connected in series with said primary windings,
first switch means connected between said primary and said secondary windings to divide said primary windings into a plurality of equal voltage steps,
a second switch means connected between said secondary windings and its output to divide said secondary windings into a plurality of equal voltage steps,
third switch means connected between said primary windings and said compensation resistance to divide said compensation resistance into a plurality of resistance steps and to connect it in series with said secondary windings so that the effective open-circuit output voltage of each step of said secondary windings is equal to the sum of the voltage induced in the last mentioned step of said secondary winding by the varying magnetic flux in said core due to the A.C. current flowing in said primary windings plus the voltage drop developed across the corresponding step of said compensation resistance by said primary winding current.
5. A precision electrical transformer comprising:
a core of magnetic material,
primary windings on said core,
secondary windings on said core,
compensation impedance means connected in series with said primary windings,
a first switch connected between said primary windings and said secondary windings to divide said primary windings into a plurality of equal voltage steps,
a second switch connected between said secondary windings and the output of said transformer to divide said secondary windings into a plurality of equal voltage steps,
a third switch connected between said primary windings and said compensation impedance to divide said compensation impedance into a plurality of impedance steps and to connect it in series with said secondary windings so that the effective open-circuit output voltage of each step of said secondary windings is equal to the sum of the voltage induced in each step of said secondary windings by the varying magnetic flux in said core due to the A.C. current flowing in said primary and the voltage drop developed across each step in said compensation impedance by said primary current, said second and third switches being mechanically ganged so that each voltage step of said secondary windings is coupled with a separate impedance step of said compensation impedance in order to compensate for the impedance voltage drop in said primary windings.
6. A precision electrical transformer apparatus comprising:
a plurality of transformers each having a core of magnetic material, primary windings on said core and a plurality of secondary windings on said core,
compensation impedance connected in series with the primary windings of the first of said transformers,
a first switch connected between the primary windings and the first secondary windings of said first transformer to divide said primary windings into a plurality of equal voltage steps,

a second switch connected between said first secondary windings and other secondary windings on said first transformer to divide said first secondary winding into a plurality of equal voltage steps,
 a third switch connected between said primary windings and said compensation impedance to divide said compensation impedance into a plurality of steps and to connect it in series with said first secondary windings so that the effective open-circuit output voltage of each step of said first secondary windings is equal to the sum of the voltage induced in each step of said first secondary windings plus the voltage drop developed across each step of said compensation impedance by the electrical current flowing in said primary, each of the remaining windings of said first transformer and the remaining transformers being connected in series by switches which divide each of them into a plurality of equal voltage steps in order to add the output voltages of said windings and obtain a final output voltage having a high degree of precision.

7. A precision electrical transformer apparatus comprising:

a plurality of voltage step down transformers each having a core of magnetic material, primary windings on said core and a plurality of secondary windings on said core,
 a first compensation impedance connected in series with the primary windings of the first of said step down transformers,
 a first switch connected between the primary windings and first secondary windings of said first transformer to divide said primary windings into a plurality of equal voltage steps,
 a second switch connected between said first secondary windings and other secondary windings on said first transformer to divide said first secondary windings into a plurality of equal voltage steps,
 a third switch connected between said primary windings and said first compensation impedance to divide said first compensation impedance into a plurality of steps and to connect it in series with said first secondary windings so that the effective open-circuit output voltage of each step of said first secondary windings is equal to the sum of the voltage induced in each step of said first secondary windings by the varying magnetic flux in said core plus the voltage drop developed across each step of said first compensation impedance by the electrical current flowing in said primary windings, each of the remaining windings of said first transformer and the remaining step down transformers being connected in series by switches which divide each of them into a plurality of equal voltage steps in order to add the output voltages of said remaining windings and obtain an output voltage having a high degree of precision,

a step up voltage transformer with its primary windings connected in parallel with the primary windings and first compensation impedance of said first step down transformer and having its secondary windings connected in series with the output of the last step down transformer so their output voltages are added thereby,

a second compensation impedance connected in series with the primary windings of said step up transformer, and

a compensation transformer connected with its primary windings in parallel with said second compensation impedance and its secondary windings in series with

the secondary windings of said step up transformer in order to correct for the impedance voltage drop in the primary windings of said step up transformer.

8. A precision electrical transformer apparatus comprising:

a plurality of voltage step down transformers each having a core of magnetic material, primary windings on said core and a plurality of secondary windings on said core,
 a first compensation impedance connected in series with the primary windings of the first of said step down transformers,
 a first switch connected between said primary windings and first secondary windings of said first transformer to divide said primary windings into a plurality of equal voltage steps,
 a second switch connected between said first secondary windings and other secondary windings on said first transformer to divide said first secondary windings into a plurality of equal voltage steps,
 a third switch connected between said primary windings and said first compensation impedance to divide said first compensation impedance into a plurality of steps and to connect it in series with said first secondary windings so that the effective open-circuit output voltage of each step of said first secondary windings is equal to the sum of the voltage induced in each step of said first secondary windings by the varying magnetic flux in said core plus the voltage drop developed across each step of said first compensation impedance by the electrical current flowing in said primary windings, each of the remaining windings of said first transformer and the remaining step down transformers being connected in series by switches which divide each of them into a plurality of equal voltage steps in order to add the output voltages of said remaining windings and obtain an output voltage having a high degree of precision,
 a voltage step up transformer with its primary windings connected in parallel with the primary windings and first compensation impedance of said first step down transformer, and having its secondary windings connected in series with the output of the step down transformers so their output voltages are added thereby,
 a second compensation impedance connected in series with the primary windings of said step up transformer, and
 a compensation transformer connected with its primary windings in parallel with said second compensation impedance and its secondary windings in series with the secondary windings of said step up transformer in order to correct for the impedance voltage drop in the primary windings of said step up transformer, and
 a switch means connected to the secondary winding of said step up transformer to change the ratio of the voltage output to the voltage input of said step up transformer.
